UNITED STATES PATENT OFFICE

KATHE PETZOLDT, OF CLEVELAND, OHIO

HAIR FASTENER

Application filed October 2, 1930. Serial No. 485,995.

This invention relates generally to hair fasteners, and particularly to an improved and novel structure of this type and possesses advantages and superiority not heretofore achieved in an article of this type.

It is an object of this invention to provide a hair fastener of the type described which may be incorporated in hair holders of various types, barettes, ribbon fasteners, and other similar articles which require to be fastened to locks of hair, and which is provided to be quickly and easily positioned and secured against coming loose, and is capable of being locked, the parts and arrangements thereof which accomplish these objects being more fully described as set out below.

These and other objects of the invention, its nature, its composition and arrangement and combination of parts will be readily understood by any one acquainted with the art to which this invention relates upon consulting the following descriptions of the drawings, in which:—

Figure 1 is a general bottom view of my improved hair fastener.

Figure 2 is a side elevation thereof showing in dotted line the open position of the locking tongue.

Figure 3 is a transverse sectional view approximately on the line 3—3 of Figure 2.

Figures 4, 6 and 7 show variations of the locking slot, to provide for different locking movements of the locking tongue, and securely maintaining the same in locking position.

Figure 5 is an end view taken on the right of Figure 2.

Figure 8 is an illustration of a form of my device in which the locking tongue and the frame of the fastener are given approximately the same curvature.

Figure 9 is a transverse vertical sectional view approximately on the line 9—9 of Figure 8.

Referring in detail to the drawings the numeral 5 designates each of a pair of side bars of an elongated rectangular frame, these side bars 5 being connected at one end by an articulate continuation of the adjacent ends of the side bars as indicated at 6, the other ends of the side bars 5 are provided with upwardly

and inwardly directed portions 7 whose inner ends are separated as indicated at 8. Transversely of the frame and in the inwardly directed portions of the end portions 7 is a pin 9 which extends across the gap 8 between the said end portions 7. The pin 9, and that portion which bridges the gap 8 functions as a pivot, at which is pivotally mounted a locking tongue 10 which is adapted to have its rounded end portion 11 rested upon the articulate portion 6 of the frame, when in locking position as shown in Figure 2. Referring again to the frame 5 the numeral 12 indicates the points at which the end portions 7 are directed upwardly, and the numeral 13 indicates the point at which the pivoted end portion of the locking tongue is directed upwardly at an angle, and the portion between said point 13 and the contiguous extremity of the locking lever is designated by the numeral 14. On its underside the portion 14 is provided with a notch 15 which is engageable by the finger nail in the unlocking operation to be hereinafter described.

In the form shown in Figure 2 the locking tongue 10 is shown to be longitudinally and upwardly bowed at a somewhat greater curvature than the longitudinal upward bowing of the side members 5 of the frame. This difference in curvature is not seen in Figure 8 which modification is better adapted to be made in large more extended fasteners, which will permit of a greater degree of flexing of the locking tongue and frame when a lock of hair is compressed therebetween, than in the case as in the short or compact form which preferably has the formation illustrated in Figure 2. Figure 3 shows the disposition of a lock of hair and the relative positions of the locking tongue and the side bars of the frame when the same is in locking association. Figure 9 illustrates the relative disposition of the locking tongue and the side members of the frame when a lock of hair is clasped therebetween by a structure made according to the modification illustrated in Figure 8.

It is thought to be obvious to those acquainted with the art to which this invention relates that in the form illustrated in Figure 8 there is not the necessity to give the frame

and the locking tongue a relatively different curvature since the relatively greater length of the members permits a relatively greater flexing movement than is possible in the instance of the form illustrated in Figure 2 which comprises a relatively short and compact frame and relatively short locking tongue. In the drawings the numeral 16 designates a lock of hair. Reference to Figure 8 will disclose the specific formation of the pivoted end portion 14 of the locking tongue. It is provided longitudinally thereof with a slot 17 in which the pin 9 engages. It is obvious that with this arrangement the locking tongue 10 may be upwardly and downwardly rocked, and relatively horizontally displaced as shown in dotted lines in Figure 2. The object of providing for a horizontal displacement is to permit the end portion 11 of the locking tongue to be brought from superposed position on the arcuate portion 6, to a position in which the said end portion 11 has a certain amount of clearance from the inside of the portion 6, whereby the locking tongue is freely permitted to fall into the position shown in dotted lines in Figure 2.

In different modifications and rearrangements of the hair fastener it is advisable and may be necessary to have slotted extensions on the slot 17 formed in enlargements 18 on the portion 14 as seen in Figures 4, 6 and 7, to provide for the clearance just spoken of. In Figure 4 the extended portion of the slot takes the form of a short arcuate slot 19, and in the form shown in Figure 6 the slot extension takes the form of a slot in the form of a curve greater than a half circle as indicated by the numeral 20. In the form illustrated in Figure 7 the slot extension takes the form of a lateral offset slot 21.

It is thought to be obvious that the slot formation illustrated in Figures 4, 6 and 7 provides for positively locking the pivoted end of the locking tongue against accidental horizontal movement, and they provide the safety, non-displaceable feature of the locking tongue, in which resides one of the chief merits of this invention. It is thought to be obvious that in the form shown in Figures 4 and 6, a horizontal and upward pressure on the end portion of the locking tongue is required to lock the said tongue, and a reverse movement is required to unlock the same. In the form shown in Figure 7 a simple horizontal and downward or upward movement is required in the locking and unlocking operations.

In attaching the hair fastener, the lock is laid upon the locking tongue and the frame brought downwardly thereupon, and then the locking tongue is given a horizontal movement so that its end portion 11 may be brought to have the proper clearance from the portion 6 of the frame, this being necessary to freely permit the upward movement

of the end portion 11 of the locking tongue, and then a reverse horizontal movement is given the tongue so as to be superposed upon the upper side of the portion 6 so as to lock the lock of hair as shown in Figures 9 and 3. 70 When this is accomplished, an extra pressure may be brought to bear upon the pivoted end of the locking tongue pressing it into the offset slot extensions illustrated in Figures 4, 5 and 7, for securely and safely locking the 75 locking tongue against accidental displacement as already stated.

It is to be definitely understood that I do not desire to limit the application of this invention to the particular modification set 80 forth above to illustrate the principle thereof, and any change or changes may be made in material or structure or arrangement of parts consistent with the spirit and scope of the invention.

What is claimed is:—

1. A hair fastener of the class described comprising an elongated frame consisting of a pair of side bars connected by a cross member at one end and having their other 90 ends inwardly directed and in axial alignment and spaced apart, a pivot pin through said axial aligned ends and bridging said space, said side bars being longitudinally and upwardly bowed; and a longitudinally and 95 upwardly bowed locking tongue having an angularly and upwardly directed end portion formed with a closed slot for pivotal and sliding engagement on said pin to permit pivotal and horizontal movement of tongue, 100 said locking tongue adapted to having its other end portion disposed upon the cross member in locking position upon a lock of hair.

2. A hair fastener of the class described 105 comprising an elongated frame consisting of a pair of side bars connected by a cross member at one end and having their other ends inwardly directed and in axial alignment and spaced apart, a pivot pin through said axial 110 aligned ends and bridging said space, said side bars being longitudinally and upwardly bowed; and a longitudinally and upwardly bowed locking tongue having an angularly and upwardly directed end portion formed 115 with a closed slot for pivotal and sliding engagement on said pin to permit pivotal and horizontal movement of tongue; said locking tongue adapted to having its other end portion disposed upon the cross member in 120 locking position upon a lock of hair, and an extension of said closed slot formed to operate as a releasable detent for maintaining said locking tongue normally against horizontal displacement from said position.

In testimony whereof I affix my signature.

KATHE PETZOLDT.
